(57) **CLAIM**

The ornamental design for interchangeable hitch handles, as shown and described.

DESCRIPTION

FIG. 1 is a perspective view of the interchangeable hitch handles according to the present invention.

FIG. 2 is a front view of the interchangeable hitch handles according to the present invention.

FIG. 3 is a left side view of the interchangeable hitch handles according to the present invention.

FIG. 4 is a rear view of the interchangeable hitch handles according to the present invention.

FIG. 5 is a right side view of the interchangeable hitch handles according to the present invention.

FIG. 6 is a bottom view of the interchangeable hitch handles according to the present invention.

FIG. 7 is a top view of the interchangeable hitch handles according to the present invention.

FIG. 8 is a front view of the top portion of the mounting shaft for the interchangeable hitch handles according to the present invention. The left side view, right side view, and rear view of the top portion of the mounting shaft for the interchangeable hitch handles according to the present invention are identical to the front view.

FIG. 9 is a top view of the top portion of the mounting shaft for the interchangeable hitch handles according to the present invention; and,

FIG. 10 is a bottom view of the top portion of the mounting shaft for the interchangeable hitch handles according to the present invention.

The broken lines shown in FIGS. 1 and 8 are for illustrative purposes only and form no part of the claimed design and the separate showing of the mounting shaft is for ease of illustration only.
